United States Patent Office

Des. 184,067
Patented Dec. 9, 1958

184,067

APPLIQUE EMBLEM OR THE LIKE

Irene B. Pavlik, Cincinnati, Ohio

Application November 2, 1956, Serial No. 43,653

Term of patent 3½ years

(Cl. D3—9)

The figure is a plan view of an applique emblem, showing my new design. The applique is of conventional thickness.

I claim:

The ornamental design for an applique emblem or the like, as shown and described.
